WILLIAM W. WADE, OF MEDFORD, MASSACHUSETTS.

Letters Patent No. 88,099, dated March 23, 1869; antedated March 5, 1869.

IMPROVEMENT IN BUTTONS.

The Schedule referred to in these Letters Patent and making part of the same.

To all whom it may concern:

Be it known that I, WILLIAM W. WADE, of Medford, in the county of Middlesex, and State of Massachusetts, have invented certain Improvements in Buttons, of which the following is a full, clear, and exact description, reference being had to the accompanying drawings, making part of this specification, in which—

Figure 1 is a perspective view, representing a flat circular plate cut from a sheet of metal.

Figure 2 is a view representing the said circular plate with its outer edge turned up, and two slits, or openings cut near its centre.

Figure 3 is a section through a button with a back of my improved construction.

Figure 4, detail, to be referred to.

My invention consists in making the back and eye of a button from one and the same piece of metal, that is to say, a back of metal with its eye, or shank, struck up, or otherwise formed therefrom, in contradistinction to a back and eye made of separate pieces of metal secured together.

To enable others skilled in the art to understand and use my invention, I will proceed to describe the manner in which I have carried it out.

A flat sheet of metal is passed under a series of punches, which cut it into circular plates, A, fig. 1.

These plates are then carried, in succession, upon a revolving table, and deposited in a horizontal position within the top of a female die of the required form.

A circular forming-punch, with a male cutting-die enclosed, now simultaneously descends, the punch striking up the periphery, or outer edge of the circular plate, and holding it firmly in place, while the cutting-die makes therein two slits, a, of the form shown in fig. 4, and then turns them up, as seen in fig. 2.

The forming-punch and male cutting-die now withdraw together, carrying with them the metal back until it is free from the female die, when the cutting-die recedes, to allow a pair of nippers to advance, and press or turn up the two inner edges, b, of the slits, or openings a, in the back, A, thus uniting the two edges

smoothly together, and forming an eye, c, fig. 3, which presents no sharp edges to cut the thread, the pincers at the same time depressing, or slightly grooving the portion of the back adjacent to the eye, in order that the thread may be more easily entered.

A button constructed with its shank, or eye struck up from a metal back, is more rigid, and not liable to break, and the thread cannot pull out, as frequently happens with the cloth back and eye.

The cloth back and eye are also objectionable, for the reason that a hole has first to be made through it by an awl, or needle, for the passage of the thread, whereas, by my improved construction, the opening for the thread is already made, and the thread may be readily entered without the employment of the awl or needle.

Again, my improvement possesses an advantage over the ordinary metal-back button, where the back is in one piece, and the eye is in a separate piece, (of wire, usually,) and connected thereto, as in such a back both ends of the thread must pass through the same hole in the work, in order to bring the back as near to and as parallel therewith as its construction will admit. It cannot, however, be brought close to the surface of the work to which it is attached, owing to the distance of the eye from the back, whereas a back of my improved construction may be drawn down snugly in contact with the work, thus giving a neater and more finished appearance, and therefore more desirable for upholsterers' purposes.

Claim.

What I claim as my invention, and desire to secure by Letters Patent, as an improvement in buttons, is—

A back, A, and eye, or shank, c, made in one and the same piece of metal, by cutting and swaging up into proper form, substantially as described.

WILLIAM W. WADE.
